UNITED STATES PATENT OFFICE.

EMIL HOUDLETT, OF BROOKLYN, NEW YORK.

ATTACHMENT FOR MUSICAL INSTRUMENTS OF THE BANJO TYPE.

Application filed January 21, 1922. Serial No. 530,970.

To all whom it may concern:

Be it known that I, EMIL HOUDLETT, a citizen of the United States, residing at Brooklyn, in the county of Kings and State of New York, have invented certain new and useful Improvements in Attachments for Musical Instruments of the Banjo Type; and I do hereby declare the following to be a full, clear, and exact description of the invention, such as will enable others skilled in the art to which it appertains to make and use the same.

This invention, while broadly applicable to musical instruments of one type or another, is designed and illustrated more particularly with reference to a banjo either of the standard or popular type.

The objects of the invention are to provide a banjo or similar musical instrument with a sound passage passing upwardly between the ring and rim; to provide improved means for supporting the band; to avoid cutting the rim in obtaining such support; to provide a support which will carry both the band and ring; to utilize the screw securing the head tightening lug or bracket to the rim for also mounting said support; to utilize the support as a washer for said screw; to provide for increased resonance in an instrument of this character; to this end to provide a back for the instrument; to permit the back to be removed readily at will; to secure simplicity of construction and assembly; to obtain rigidity, compactness, neatness, improved tone, and to obtain other advantages and results as may be brought out in the following description.

Referring to the accompanying drawing in which like numerals of reference indicate similar parts throughout the several views;

Figure 1 is a plan or face view of a banjo embodying my invention;

Figure 2 is an enlarged sectional view through the edge of the same showing one of the supports, and

Figure 3 is a perspective view of one of the supports.

In the specific embodiment of the invention illustrated in said drawing, the reference numeral 1 indicates the rim of the banjo which is shown as cylindrical and preferably made of wood, forming the base or body upon which the rest of the banjo is built. It is important both for strength and for obtaining the best musical tone of

the instrument that this rim be uniform and not notched or cut out around its edge. I accordingly provide a support 2, comprising one of the features of the present invention, which has a transverse portion 3 adapted to engage flatwise upon the upper edge of the rim 1, extending across the same in a radial direction. The outer part of the support beyond the portion 3 is bent downwardly to provide a depending portion 4 which will engage at the side of the rim and which is bent outwardly at its lower end to provide a hook 5. At the inner side of the rim 1 the support is bent downwardly from the portion 3, as at 6, and is then bent inwardly again, as at 7, thus providing an offset shoulder upon which the resonating ring may be mounted in the assembled instrument. The material comprising the support is again bent downwardly inward from the end of the shoulder and brought into engagement with the inner surface of the rim so that the lower portion 8 of the support may rest flatwise against said rim. The support thus formed may be slipped onto the rim so that the depending portions 4 and 8 are upon opposite sides thereof and prevent movement of the support in a radial direction with respect to the rim.

Preferably the inner depending portion 8 is somewhat longer than the outer depending portion 4, and terminates in an eye 9 which will act as a washer for the screw 10 inserted therethrough after the support is in place. As shown, the screw 10 is inserted from the inner side of the rim, projecting out through the same and screwing into the bracket 11 which acts both as a nut for the screw and also as a lug for a suitable head tightening device.

It is to be understood that the supports 2 are distributed at spaced intervals around the rim, as indicated in Figure 1, and after the same have been positioned and secured, a band 12 is slid into place around the rim overlying the depending portions 4 of the supports in sufficiently close proximity thereto to enable the hooks 5 at the lower ends of said depending portions to engage under the edge of said band and support the same. The head or skin 14 is then laid across the ring and band, and a hook 13 is forced downwardly over the band and skin tightening the skin across the ring and turning its edge downwardly between the hoop and band. The hoop is then drawn further down by the

- tightening means heretofore referred to and which is shown in the present instance as comprising a hooked rod 15 the lower end of which passes through the bracket 11 and is 5 screw threaded for receiving a suitable thumb nut 16 below the bracket. It will be observed that by this construction I obtain a very solid construction but at the same time simple and inexpensive to manufacture.
- 10 It is also to be observed that by the construction disclosed the support 2 permits the ring to be mounted in spaced relation from the rim thus allowing the air and tone waves to pass therebetween. Likewise, there is a 15 space between the band 12 and the rim 1 allowing passage of the air and tone waves to the outside of the instrument, thereby greatly increasing the volume and resonance thereof.
- 20 As an additional feature of the present instrument, I have shown a back 17 for closing over the opening opposite the head or skin 14 so as to obtain increased resonance of the sound which adds greatly to the richness of the tone. Any suitable means may be 25 employed for the attachment of the back to the rim, and for purposes of illustration I have shown snap fasteners 18, although other means may be employed as found desirable. Furthermore, I have shown the 30 back spaced slightly from the rim in order to leave a sound passage 19 therebetween, but it is to be understood that this may be varied as found desirable in the manufacture of 35 this or similar instruments.

Having thus described my invention, I claim:

1. A U-shaped bracket attachment for banjos or the like, having an eye at the end

of one leg and a hook at the end of the other leg, with means intermediate the legs to engage the banjo rim and to support the banjo ring.

2. In a musical instrument of the banjo type having a rim, an inner ring and an outer band, a plurality of U-shaped supports, embracing said rim each with one leg upon the inside and one leg upon the outside of said rim, with means on one leg for mounting the inner ring and means on the other leg for mounting the outer band.

3. In a musical instrument of the banjo type having a rim, a ring of less diameter than said rim and a band of greater diameter, a support having an eye at one end for securing the same within and to the rim and having a shoulder for supporting the ring, said support being bent so as to project over the edge of the rim and against the outside of the same and having a hook at its outer end for supporting the band.

4. In a musical instrument of the banjo type having a rim, a ring of less diameter than said rim and a band of greater diameter, a support having an eye at one end for securing the same within and to the rim and having a shoulder for supporting the ring, said support being bent so as to project over the edge of the rim and against the outside of the same and having a hook at its outer end for supporting the band, whereby the band and the ring 9 are spaced from the rim and sound may pass from the interior of the instrument over the edge of the rim and between the ring and band.

75 In testimony whereof I affix my signature.

EMIL HOUDLETT.
